178,091

WATCH OR SIMILAR ARTICLE

Lawrence W. Sparks, Bergen County, N. J., assignor to Vacheron & Constantin-Le Coultre Watches, Inc., New York, N. Y., a corporation of New York

Application September 14, 1955, Serial No. 37,927

Term of patent 14 years

(Cl. D42—8)

FIG. 2

FIG. 3

Fig. 1 is a top plan view of a watch or similar article, showing my new design;

Fig. 2 is a bottom plan view thereof; and

Fig. 3 is a side elevational view thereof.

I claim:

The ornamental design for a watch or similar article, substantially as shown.
